UNITED STATES PATENT OFFICE.

WILLIAM C. ANDERSON, OF TOLEDO, OHIO, ASSIGNOR TO THE LIBBY GLASS COMPANY, OF SAME PLACE.

DESIGN FOR THE ORNAMENTATION OF GLASSWARE.

SPECIFICATION forming part of Design No. 22,098, dated January 3, 1893.

Application filed November 19, 1892. Serial No. 452,588. Term of patent 3½ years.

To all whom it may concern:

Be it known that I, WILLIAM C. ANDERSON, of Toledo, in the county of Lucas and State of Ohio, have invented a new and original 5 Design for the Ornamentation of Glassware, of which the following is a specification.

The class to which this design relates is that of ornamentation of glassware, and the design pertains to the ornamentation of the 10 exterior surface thereof.

The drawings represent, in Figure 1, a bottom plan view of a dish containing the design, and in Fig. 2 a transverse section on lines x x , Fig. 1.

15 The design is applicable to any kind of glassware, such as bowls, plates, jugs, and dishes.

The leading features of my design are the 20 alternating figures a b , arranged in rows, two of which extend across the dish substantially at right angles to each other, and constitute a cruciform figure, while the others extend along the marginal portions of the dish and 25 form a substantially rectangular border, which is subdivided by the cruciform figure

into four smaller substantially rectangular fields or figures $c c c c$. The central portions of the figures a and b are ornamented by a fine net work of lines forming fields surrounded by the plain marginal portions of 30 said figures. Each of the rectangular fields or figures c is subdivided and broken up by ornamentation consisting principally of the central figure 2 and the figures 3 3 3 3 subdividing said central figure. 35

I claim:

The design for the ornamentation of glassware herein described, the same consisting of the cruciform figure and the substantially rectangular marginal figure, each composed 40 of rows of smaller figures, as set forth.

In testimony whereof I have signed my name to this specification, in the presence of two subscribing witnesses, this 10th day of November, A. D. 1892.

WILLIAM C. ANDERSON.

Witnesses:

FREDERICK L. GEDDES,
WILLIAM A. MILLS.
